UNITED STATES PATENT OFFICE

93,815

DESIGN FOR AN ELECTRIC GLASS AUTO TIRE SIGN

Leonard H. Coble, Wichita, Kans.

Application August 14, 1934, Serial No. 52,950

Term of patent 7 years

To all whom it may concern:

Be it known that I, LEONARD H. COBLE, a citizen of the United States, residing at Wichita, in the county of Sedgwick and State of Kansas, have invented a new, original, and ornamental Design for an Electric Glass Auto Tire Sign, of which the following is a specification, reference being had to the accompanying drawing, forming part thereof.

Figure 1 is a view in front elevation of the sign showing my new design.

Figure 2 is a view in side elevation of the same.

I claim:

The ornamental design for an electric glass auto tire sign, as shown.

LEONARD H. COBLE.
